United States Patent Office

Des. 203,848
Patented Feb. 22, 1966

203,848

CLOCK OR SIMILAR ARTICLE

Neil Staib, Cincinnati, Ohio, and William V. Judson,
Westport, Conn., assignors to General Electric Com-
pany, a corporation of New York

Filed Mar. 25, 1965, Ser. No. 84,435

Term of patent 14 years

(Cl. D42—7)

Fig. 1.

Fig. 2.

Fig. 5.

FIG. 1 is a front perspective view of a clock embodying our new design;

FIG. 2 is a top plan view thereof;

FIG. 3 is a side elevational view thereof;

FIG. 4 is a front elevational view thereof; and

FIG. 5 is a rear elevational view thereof.

We claim:

The ornamental design for a clock or similar article, substantially as shown.
